UNITED STATES PATENT OFFICE.

HENRY TEXTOR, OF BROOKLYN, NEW YORK, ASSIGNOR TO J. S. & G. F. SIMPSON, OF SAME PLACE.

DESIGN FOR A NEWEL-POST.

SPECIFICATION forming part of Design No. 12,025, dated November 9, 1880.

Application filed August 28, 1880. Term of patent 7 years.

To all whom it may concern:

Be it known that I, HENRY TEXTOR, of the city of Brooklyn, in the county of Kings and State of New York, have originated and produced a new and Improved Design for Newel-Posts, of which the following is a specification.

The character of my design is clearly shown in the accompanying drawing, which represents a perspective view of a newel-post embodying my design.

The base A is composed of a polygonal or rectangular portion, *a*, having flat faces, a surmounting convex molding, *b*, a hollow molding, *c*, and a flat-faced band-like molding, *d*.

The body portion B of the post is polygonal in its horizontal section and tapers slightly from its lower end upward. Upon each of its sides or panels, near the lower corners, are scroll ornaments *e*, between and slightly above which are striated ornaments *f*, consisting of parallel lines. At about the center of each side are scrolled ornaments *g g*, which are made right and left and arranged upon each side of and slightly away from a central line, *h*. In the center of each side, near the top, is a sunken rose or rosette, *i*.

The capital or cap C of the post is composed

of a variety of ornaments, there being, first, a bead, *j*, a surmounting outwardly-projecting molding, *k*, the top of which inclines inward, a convex molding, *l*, having a fillet, *m*, above and below it, and an urn-like finial ornament, *n*.

What I claim as my invention, and desire to secure by Letters Patent, is—

1. A design for the side or panel of a newel-post, consisting of the right and left scroll ornaments *g g* and the central sunken rose or rosette, *i*, as specified.

2. A design for the side or panel of a newel-post, consisting of the corner scroll ornaments *e*, the striated ornaments *f*, the right and left scroll ornaments *g g*, and the sunken rose or rosette *i*, as specified.

3. A design for a newel-post, consisting of the base A, the body B, having the right and left scroll ornaments *g g*, and the sunken rose or rosette *i* upon each face, and the molded cap C, as specified.

HENRY TEXTOR.
